UNITED STATES PATENT OFFICE.

HENRY H. LAMPERT, OF CHICAGO, ILLINOIS.

HEAD BRACKET FOR SHORES.

Application filed May 25, 1925. Serial No. 32,702.

The main objects of this invention are to provide an improved form and arrangement of head bracket for shores and struts; to provide a head bracket for struts having an improved form of frame member for receiving the rectangular posts commonly employed for the shores of a building; to provide a head bracket having an improved form of compression members; to provide an improved relative arrangement of the beam and compression members; and to provide improved means for securing the compression members and frame member to the beam.

15 An illustrative embodiment of this invention is shown in the accompanying drawing, wherein—

Fig. 1 is a perspective view of an improved T-head bracket to which this invention is applied, part of a strut being also shown.

Fig. 2 is an enlarged detail in elevation showing a corner of one of the angle bars forming the frame member.

25 Fig. 3 is an enlarged detail in elevation showing a corner of one of the compression members.

The common form of T-head brackets heretofore in use have included a metallic beam mounted on a central frame member, and braced by a plurality of compression members which projected above the metallic beam for holding a wooden beam, supported on the metallic beam, against lateral displacement.

35 The improved T-head, to which the present invention is applied, omits the metallic beam member and, by reason of the improved form and arrangement of parts, the wooden beam is supported on and directly connected to the frame and compression members.

In the specific construction herein shown, the improved T-head bracket comprises a 45 rectangular frame 1 of the desired shape and size in cross section to telescopically engage a strut or post 2, and having supported thereon, a wooden beam member 3, to which the false work or other timbers may be nailed, and which is braced by a pair of compression members 4. The upper end of the frame 1 rests on top of the post 2, but for the sake of clearness part of the post is broken away in the drawing.

55 In the form shown, the frame 1 comprises a pair of angle bars 5, bent to inverted

U-shape and arranged in substantially parallel spaced relation. The upright legs of the U-shaped bars 5 are arranged so as to form guideways which slidably engage the corners of the post 2. To prevent buckling of the angle bars 5 at the points of bending, the flange 6, which is located at the inside of the bend, is slit and a portion thereof cut away, as shown at 7, so that the corners 65 present a finished appearance.

The lower ends of the frame members 5 are connected together by means of straps 8 which are riveted or otherwise rigidly secured thereto, as shown at 9. The upper 70 ends of the inverted U-shaped members 5 are arranged to form a transverse seat 10, on which the wooden beam 3 rests. Formed in the seat 10, are apertures 11 for receiving bolts 12, which extend through the beam 3 75 for detachably securing it to the frame 1.

The compression members 4 are preferably angle bars which are bent to V-shape, and which are secured to one leg of each of the frame members 5 by rivets 13 or other 80 suitable fastening means. To facilitate bending of the compression members 4, the flanges 14 thereof are slit at the points of bending, as shown at 15. The upper ends of the compression members 4 extend above the 85 plane of the frame seat 10, and are apertured to receive bolts 16, which extend transversely through the wooden beam 3.

From the foregoing description it will be apparent that the improved form and arrangement of parts herein shown and described provide a head bracket which is inexpensive and simple, and which is adapted for use in connection with many different types of shores.

Although but one specific embodiment of this invention has been herein shown and described, it will be understood that certain details of the construction shown may be altered or omitted without departing from 100 the spirit of this invention as defined by the following claims.

I claim:

1. A head bracket for shores comprising a pair of inverted U-shaped members arranged in substantially parallel spaced relation to form a rectangular frame, the upper ends of said members forming a transverse seat, a beam supported on said seat, and rigidly secured directly to the upper ends of 105 said U-shaped members, a pair of V-shaped compression members connecting said U-

shaped members together, and fastening means for securing said beam to said compression members.

2. A head bracket for shores comprising a pair of inverted **U**-shaped members arranged in substantially parallel spaced relation to form a rectangular frame, the upper ends of said members forming a transverse seat having apertures therein, a beam supported directly on said seat, bolts extending through said apertures and beam for securing the latter to said seat, and a pair of **V**-shaped compression members connecting said **U**-shaped members together and having the upper ends thereof connected to said beam.

3. A head bracket for shores comprising a pair of inverted **U**-shaped members arranged in substantially parallel spaced relation to form a rectangular frame, the upper ends of said members forming a transverse seat having apertures therein, a beam supported directly on said seat, bolts extending through said apertures and beam for securing the latter to said seat, straps connecting together the lower ends of said members, a pair of **V**-

shaped compression members connected to one leg of each of said **U**-shaped members and having their upper ends projecting above the plane of said seat, and other bolts 30 extending transversely through said beam and the upper ends of said compression members.

4. A head bracket for shores comprising a pair of angle bars bent to inverted **U**-shape and arranged in substantially parallel spaced relation to form a rectangular frame, one flange of each of said angle bars forming a transverse seat at the upper end of said frame, the other flange of each of said angle bars being slit at the points of bending, a wooden beam supported on and secured directly to said seat, and another pair of angle bars bent to **V**-shape to form compression members connected to said frame and having the upper ends thereof extending above the plane of said seat and secured to said beam, one flange of each of said compression members being slit at the point of bending.

Signed at Chicago this 20 day of May, 50
1925.

HENRY H. LAMPERT.
